UNITED STATES PATENT OFFICE.

WILLIS L. CUTLER, OF LEGRAND, IOWA, ASSIGNOR TO FRANK R. ENSMINGER, OF GILMAN, IOWA.

MULTIPLE CONCRETE-BLOCK MOLD.

1,285,056.

Specification of Letters Patent. Patented Nov. 19, 1918.

Application filed May 31, 1917. Serial No. 171,826.

To all whom it may concern:

Be it known that I, WILLIS L. CUTLER, a citizen of the United States, residing at Le-
grand, in the county of Marshall and State
5 of Iowa, have invented certain new and
useful Improvements in Multiple Concrete-
Block Molds, of which the following is a
specification.

This invention relates to multiple con-
10 crete block mold and has for its principal
objects to produce a mold in which a plu-
rality of concrete blocks can be formed by
a single pouring; to produce a mold that
can be easily set up and taken down; to
15 produce a mold in which a two part con-
crete block can be cast; to produce a con-
crete block forming mold which can be
taken down before the blocks are completely
dried without injury to the blocks; to
20 produce a plural block mold which can
be used a plurality of times; to produce a
mold in which slush concrete blocks can be
formed; to produce a multiple concrete
block mold so organized that slush concrete
25 when poured will flow to all parts thereof
from a single point of pouring; to provide
a mold in which concrete blocks can be
formed from slush concrete; to produce a
mold in which concrete blocks can be formed
30 which are made up of two parts tied to-
gether; to produce a mold for making wire
spaced apart two part concrete blocks in
quantities by a single operation; to provide
a mold frame made up of a plurality of
35 separate units; to produce a mold frame in
which the units thereof are constructed so
that communicating passageways are af-
forded between the various sections of the
mold; to produce an extremely simple mold
40 that is inexpensive to manufacture, and,
in general to produce a unitary concrete
block mold of the class referred to.

Further objects not above referred to will
appear from an examination of the specifi-
45 cation and drawings.

In the accompanying drawings;

Figure 1, is a perspective view of the mul-
tiple concrete block mold, parts being
broken away to more clearly show the in-
50 terior.

Fig. 2, is a side elevation of one of the
longitudinal units.

Fig. 3, is a sectional transverse elevation
of two of the units.

Fig. 4, is a similar view to that shown in 55
Fig. 3 showing the division plate and wires
in position.

Fig. 5, is a perspective view of one of the
blocks produced by the mold.

Fig. 6, is a plan view of one half of the 60
mold.

Fig. 7, is a longitudinal section elevation
showing the method of casting a corner
block, and

Fig. 8, is a perspective view of a portion 65
of the mold showing the corner block core
in position.

Referring to the drawings the mold is
provided with end plates 11 and 12 and side
plates 13 and 14. The plates 11 and 12 have 70
their upper and lower edges bent inwardly
back upon themselves as shown at 15 so as
to furnish added strength. The end plates
11 and 12 are also provided with a plurality
of openings 16 and the side plates 13 and 75
14 are each provided with a single opening
17 similar to opening 16, the function of
these openings will hereafter appear.

The units shown at 18 in Fig. 1 and in
detail in Fig. 2 are composed of two mem- 80
bers, the upper one 19 being U-shaped and
inverted when in position, the lower one 21
being similar in outline but in normal U
position.

The end plates 11 and 12 are cut away 85
as shown at 20 to furnish means for holding
the ends of the units in position. Each
upper member 19, five being shown in the
present construction, has a pair of flanges
22. These flanges are bent slightly down- 90
wardly out of horizontal position as shown in
Figs. 3 and 4. Each lower member 21 has
similar flanges 23, but considerably shorter,
which are bent upwardly. The two U shaped
members are permanently secured together 95
by spacers 24 inserted between the sides
of the U and riveted or otherwise se-
cured therein. There is a plurality of these
spacers throughout the length of each unit
18, and the end ones have secured thereto 100
a strap 26. This strap is bent so that its
outer end lies in a horizontal plane and is
provided with an opening 27. This outer
end is adapted to project through openings
16 in the end plates 11 and 12. A wedge 28 105
is adapted to be inserted in the opening 27
thereby firmly securing each unit 18 in place
and securely holding the end plates 11 and

12 against outward movement. A similar locking device is used to secure the side plates 13 and 14 against movement. The only difference being that the strap instead of being short extends clear across from side to side as at 29 and is positioned midway between the end plates 11 and 12. These end plates 11 and 12 are provided at their ends with flanges 31 similar to flanges 15 10 to assist in holding the parts in position.

Transversely of the mold are two rows of partitions, each row, in the present device, is composed of five partitions 32, Figs. 1 and 6. These partitions are each made up 15 of two opposed U shape members 33 and 34. They are linked together and held in spaced apart relationship by spacers 36. In order to hold these partitions 32 in position the flanges 22 and 23 of each U 19 and 21 are 20 slotted as at 37. As thus positioned they are prevented from moving longitudinally by the members 19 and 21 and from sidewise movement by flanges 22 and 23. The end partitions 32 have their outer edges held in 25 slots in the flanges 38 of the side plates 13 and 14.

The flanges 22 of the U members 19 of the longitudinal units 18 are each provided with a series of openings or slots 39 in 30 their outer edges. The end flanges 38 are also similarly furnished with openings 39. These openings 39 are designed to receive wires 41.

Referring now to Figs. 7 and 8 these views 35 show the method of casting a corner block. The essential feature of this is a core 42 which is made up of a short side 43, a long side 44 and a base. Each side of this base is provided with slots 46 for the reception 40 of wires 47 similar to wires 41 and a corner wire 48. The partition 32 in this instance being solid so that the concrete cannot flow from the space between the core and the partition into the space beyond the partition 32. The flange 22 of the member 19 45 being cut away as at 49 to permit the corner block to be cast with a slot, which would occur if this flange remained uncut. Referring back to Fig. 1, and particularly the 50 longitudinal units 18; on the upper surface of the two flanges 22 that face each other of the adjacent members 19, and between the wires 41, is placed a division plate 51 as is shown in Figs. 1 and 4. These plates are 55 of a length equal to the distance between two partitions 32 and of a width equal to the distance between the wires 41 of opposite flange 22.

The method of procedure is as follows: 60 After the mold has been set up and locked, as is apparent from the foregoing description, it is placed upon five pallets, one for each row of three blocks; slush concrete is now poured into the mold until it reaches 65 the level of the top of the flanges 23, as

shown in Fig. 3. A scraping tool is now used to stroke off or smooth the upper surface of the concrete. It is of course understood that this concrete is still very soft. The next step is to place the wires 41 in 70 the holes 39 and press them down into the soft concrete mass as clearly shown in Fig. 4; then the plates 51, one for each block, are set down upon the flanges 23 and between opposite sets of wires 41. This leaves 75 an air space 53 between the top of the lower half of the block and the plate 51. Now concrete is poured into the upper half of the mold up to the tops of the U's 19 and 33, the plates 51 serving as the bottom of the 80 upper half of the block. The excess material is now scraped off making the upper surface smooth. In stroking off the upper surface of the lower half of the block the openings through the units 18 and the partitions 32 serving as convenient means for 85 getting rid of the excess material in any one section by permitting it to run into the next adjacent one.

When the mold has been completely filled, 90 it is allowed to stand until the slush concrete has sufficiently hardened so that the blocks will retain their shape when standing alone. The pin 28 is now removed. This permits the side plate and end plates to 95 drop away from the remainder of the mold. After the two partitions in the first section of the mold have been removed, the pallet on which the three blocks of the first section rests is slid sidewise sufficiently to permit the next unit 18 to be removed. This process is continued until all the frame members of the mold have been separated 100 from the blocks. During the time when the blocks are separated from the mold, and 105 when completely dried so that they can be handled, the mold may be used for the next operation. The core 42 for the corner block of course, cannot be removed until the blocks 110 can be handled as it must be pulled out downwardly.

Various modifications and changes may be made without departing from the scope of the invention as defined by the appended claims.

I claim:

1. In a mold frame; a plurality of longitudinal and transverse members for dividing the frame into sections; said longitudinal members being of folded, double wall construction and provided with integral flanges; and a division plate adapted to rest on said flanges for separating the sections into upper and lower compartments.
2. In a knock-down frame for forming 125 blocks, composed of two-parts having bevelled facing edges and provided with reinforcing stay-wires, a plurality of two-part U-shaped members secured together, spacing straps projecting into and uniting said U- 130

shaped members, and a plurality of sectional transverse members dividing said frame into sectional compartments.

3. In a take-down frame for casting two-part concrete blocks connected together by tie-wires, longitudinal and transverse members for dividing said frame into compartments, integral, oppositely facing, flanges formed from said longitudinal members and having notches therein for holding said tie-wires, and a division plate for each compartment adapted to retain the tie-wires in said notches.
4. In a take-down frame for casting two-part concrete blocks connected together by a double row of tie-wires, longitudinal and transverse members for separating said frame into compartments, integral opposed flanges formed from said longitudinal members having notches therein for the reception of said tie-wires, and a division plate adapted to lie on said flanges and between said double row of tie-wires for holding the tie-wires in position.
5. In a take-down frame for molding a plurality of double blocks secured together by tie-wires, a plurality of longitudinal members for dividing said frame into longitudinal channels, said longitudinal members comprising upper and lower parts se-

cured together so as to leave a space therebetween and provided with outstanding flanges, and a plurality of transverse members for dividing said longitudinal channels into block molds, said transverse members also being composed to upper and lower parts furnishing spaces therebetween, said spaces forming passageways whereby plastic block material may pass therethrough.

6. A collapsible mold for making a plurality of two part concrete blocks, comprising end and side plates, a plurality of longitudinal units, two opposed U-shaped members constituting each longitudinal unit, spacers on each of said U-shaped members having oppositely extending flanges, the flanges of the upper U-shaped member having notches therein for receiving and positioning tie-wires, a strap at each end of each longitudinal unit adapted to enter openings in the end plates, a key for locking said straps in position on said end plates, a plurality of partitions extending transversely of said longitudinal dividing units adapted to lie between each adjacent pair of said units for separating the longitudinal channels formed by said units into individual block forms, and a transverse connecting member for holding said mold together.

WILLIS L. CUTLER.
